UNITED STATES PATENT OFFICE

RALPH A. LIGHT, OF CYNWYD, AND JOSEPH W. PRICE, JR., OF PHILADELPHIA, PENNSYLVANIA, ASSIGNORS TO THE UNITED STATES METALLIC PACKING COMPANY, OF PHILADELPHIA, PENNSYLVANIA, A CORPORATION OF PENNSYLVANIA

SANDING APPARATUS FOR LOCOMOTIVES

Application filed June 13, 1930. Serial No. 460,854.

Our invention relates to locomotive sanding apparatus and has for its object to provide in connection with a trap having a cleaning nozzle directed into its outlet passage and a sand delivery air nozzle directed into its sand holding chamber, a valve located in the air delivery pipe shiftable in its casing into positions in which it will alternately connect and disconnect the air nozzles in the trap with the supply pipe and provided with actuating means which normally hold it in position to connect the cleaning nozzle and which shift the valve to connect the delivery nozzle with the air supply conduit when air under pressure is admitted to the conduit so that when air is turned on to operate the sander it will first flow in considerable volume to the cleaning nozzle and immediately afterward will be cut off from the cleaning nozzle and directed into the delivery nozzle. It is however desirable that a reduced flow of air should be directed into the delivery pipe of the trap at the same time that the delivery nozzle is in operation and a further object of our invention is to provide an improved construction of sand trap whereby this desirable result can be secured. The novel features of our improved trap consist in forming in its walls two air receiving chambers adapted to be connected to the two delivery ports of the automatic valve and connected respectively with an air nozzle leading into the delivery passage of the trap and an air nozzle directed into the sand holding chamber of the trap and in providing the chamber connected with the sand delivery nozzle with an additional nozzle leading into the delivery passage of the trap so that after the chamber connected with the main cleaning nozzle is cut off from the air supply a portion of the air directed into the other chamber will still be directed into the delivery passage in the trap through the supplemental cleaning nozzle. By preference we make the two cleaning nozzles concentric with each other and by preference we provide in connection with the chamber connected with the sand delivery nozzle a regulating valve controlling the air delivery into the chamber. Our invention also consists in

various details of our preferred construction all of which will be best understood as described in connection with the drawings which illustrate our improvements and in which

Figure 1 is a side elevation of a locomotive provided with our improvements. 55

Figure 2 is a plan view of the sander.

Figure 3 a sectional elevation of the sander taken on the line 3-3 of Fig. 2. 60

Figure 4 a sectional elevation of the automatic control valve taken on the line 4-4 of Fig. 5 with piston in upper position and

Figure 5 a sectional elevation of the valve taken on the section line 5-5 of Fig. 4 with 65 piston in lower position.

A indicates a locomotive; B¹, B² and B³ the driving wheels; C the ordinary sand box. D is the sander of, generally speaking, ordinary construction, with the exception of 70 the novel features to be hereafter described; the sander has a sand containing chamber. D and D¹, Fig. 1, sand traps. These traps are of ordinary construction, as shown in Figs. 2 and 3, having a sand chamber D² 75 into which sand is delivered through a pipe E or E¹ leading from the sand box and having a delivery end D⁴ separated from the portion D² by a dam-like structure as indicated at D³. Sand traps are connected as 80 usual with sand delivery pipes S or S¹ leading to the track in proper relation to certain driving wheels. Coming now to the novel features of our trap, F is an air chamber connected with a port F¹, the effective area of 85 which is controlled by a valve indicated at G, the port receiving air through a branch L² leading from a valve located in the air conduit. From the air chamber F leads a nozzle port J² directed into the portion D² 90 of the trap and a nozzle J directed into the delivery end D⁴ of the trap. K indicates another air chamber formed in the delivery end of the trap receiving the air from the conduit L³ and delivering it into the delivery 95 end of the trap through a nozzle J¹, preferably formed as shown concentric with and surrounding the nozzle J.

L and L¹ are air delivery conduits to which air is admitted and cut off by means of a 100

valve as indicated at M. Each of these conduits connects with a valve chamber indicated at N and N¹. This valve chamber is as shown cylindrical in form and is provided with laterally extending ports indicated at 10 O¹ O¹ with which connect branch conduits indicated at l² and l³ with regard to the right hand trap shown in Fig. 1, similar conduits being indicated at L² and L³ as leading out of the left hand trap. From the bottom of 15 the cylindrical chamber indicated at O in Figs. 4 and 5, leads a vent passage indicated at O⁶, which, as shown, leads from the bottom of a spring seat O⁵ formed in the bottom head of the cylinder. O² O² are similar lateral ports leading from the lower portion of the cylinder O and connected by branch pipes l⁸ l⁹ with the trap, similar pipes being indicated at L⁸ with regard to the left hand trap indicated in Fig. 1. The cylindrical valve chamber is also provided with an intermediate port O⁸ which is connected with one of the air delivery pipes L or L¹. P is a piston valve movable in the cylindrical valve chamber O, having as shown a hollow upper head P¹ and a lower head P² in which is formed as shown a spring seat P⁸. Intermediate the ends of the cylindrical valve is formed the circumferential chamber P⁴ of such length 25 that in both upper and lower positions of the valve it will register in part at least with the port O⁸ while in the upper position of the valve the chamber will register with the ports O¹ and in the lower position of the 30 valve with the ports O². A passage or port P⁵ of restricted area leads from the chamber P⁴ into the hollow head P¹ of the piston valve. Q is the spring which normally holds the valve in the upper position indicated in 35 Fig. 4 but permits its downward movement to the position shown in Fig. 5 when air under pressure is admitted to the hollow head of the valve and the upper end of the cylinder O. 40

45 It will be understood that the valves indicated at N and N¹ connect with sand traps on both sides of the locomotive.

In operation it will be understood that the valve M is normally in a position in which it 50 cuts off the admission of air to both of the pipes L and L¹ and that by shifting this valve air can be admitted to either of the pipes L or L¹ at will. This is familiar construction and needs no further showing or 55 explanation. Assuming that air is admitted to the conduit L¹ it enters the valve chamber indicated at N¹ through the port O⁸ in the cylinder body of the valve and the valve being in its uppermost position, as shown in Fig. 4, the air passes freely through the ports O² into the branch conduits L² L³ connecting with the ports F¹ of the sand traps and with the chamber F, from which the air passes through the delivery nozzle J² into 60 the sand chamber D² of the trap and through 65 the nozzle J into the delivery passage of the valve. The area of the conduit F¹ is regulated by the valve G so that a comparatively restricted flow of air is permitted to the nozzles J and J² only enough being required to insure the delivery of a proper amount of sand from the trap to the rail. The particular advantage of the nozzle J is that air flowing through it intercepts the sand coming from the sand chamber of the trap and tends to direct it downward into the delivery passage without permitting it to impinge to an undesirable extent upon the walls of the trap. 70

As soon as the air is admitted to the port O³ and cylindrical chamber P⁴ it will of course pass through the restricted port P⁵ into the upper end of the cylinder and after a very short interval will, acting on the head P¹ of the valve P, press it down to the position shown in Fig. 5. This downward motion of the valve cuts off the connection between the ports O³ and ports O¹ and opens a connection between the port O³ and ports O² through which the air will pass freely to the branch conduits L⁸ l⁹ from which it passes through the chamber K in the sand trap and escapes in considerable volume and at considerable pressure through the nozzle J¹. This is desirable in order to clear the delivery pipe S or S¹ of any obstructions. 80

It will be understood that the essential feature of our invention lies in the provision of an automatic valve located in the air conduit leading to a sand trap and in effect actuated by the pressure of air in the conduit by means of which on the turning on of air into the conduit there is first a free admission of air into the delivery end of the trap followed immediately by a restricted flow of air 90 through the sand delivery nozzle and preferably through a secondary nozzle directed like the cleaning nozzle into the delivery passage of the trap. Our preferred construction of apparatus for effecting this is obviously capable of considerable modification and change and is only to be understood as specifically called for in the claims where its parts are so called for. 95

Having now described our invention, what we claim as new and desire to secure by Letters Patent, is:

1. A sand trap having two air delivery nozzles directed into its delivery passage and connected to separate air chambers formed in the trap and a third air nozzle connected to one of the air chambers formed in the trap arranged to act upon the sand in the sand holding chamber of the trap and carry it into the delivery passage thereof. 105
2. A sand trap having the features of claim 1 in which the two air nozzles directed into the delivery passage are concentric. 115
3. A sand trap having the features of claim 1 in which one of the air chambers is 125

provided with a valve for regulating the delivery of air thereto and in which the air nozzle directed into the sand receptacle is connected to said chamber.

- 5 4. A locomotive sander mechanism comprising in combination an air supply pipe having a valve for controlling the admission of air thereto, a sand trap having a cleaner nozzle directed into the delivery outlet of the trap and a sand delivery air nozzle directed into the sand holding chamber of the trap, a valve casing having an inlet port connected to the air supply pipe, delivery ports connected respectively with the cleaning and delivery nozzles of the trap and an air chamber connected to the admission port, a valve shiftable in the casing to alternately connect and disconnect the delivery ports with the admission port, means acting to normally 10 hold and return the valve to its position connecting the delivery port leading to the cleaning nozzle and means located in the air chamber of the casing operated to shift the valve to connect the delivery port leading 15 to the delivery nozzle as air pressure accumulates in said air chamber.
